UNITED STATES PATENT OFFICE.

NICHOLAS SCHOLTES, OF MOBILE, ALABAMA.

TOOL-BOX.

1,322,354.

Specification of Letters Patent.

Patented Nov. 18, 1919.

Application filed September 13, 1918. Serial No. 253,995.

To all whom it may concern:

Be it known that I, NICHOLAS SCHOLTES, a citizen of the United States, residing at Mobile, in the county of Mobile and State 5 of Alabama, have invented new and useful Improvements in Tool-Boxes, of which the following is a specification.

This invention relates to a tool box, and the object is to provide an article of the 10 type indicated which shall be especially adapted for carrying tools and supplies of various kinds and shall include a receptacle proper with certain novel means for closing the one side and the upper portion of the 15 receptacle.

With the foregoing and other objects in view, the invention consists in the novel construction, combination and arrangements of elements hereinafter described and claimed.

20 In the accompanying drawings:

Figure 1 is a view in end elevation.

Fig. 2 is a vertical transverse section.

Fig. 3 is a side elevation.

Fig. 4 is a longitudinal section.

25 The tool box includes a bottom member 10, a rear wall 12, an upper stationary wall 13, and certain means described below for closing the front portion of the box and a portion of the top thereof. A drawer or 30 drawers 15 may be located in the position shown, one guide or track member therefor being designated 16, and the opposite guide being shown at 17. A catch or locking device 18 for the drawer is located on the inner side of one of the end members 20 and serves to prevent the opening of the drawer until the box itself has been opened. The drawer is provided with a suitable pull 22. An upper drawer 5 is located below the stationary portion of the cover designated 13, this drawer being movable toward the main opening in the box and being retained in position by the cover referred to below when

the latter is secured. A slide for this drawer 5 is provided at each end of the box, these 45 slides being designated 7 and 8.

The front of the tool box is designated 25 and guides 26 are located at the ends of the front sections and receive the upper removable section 27 when the latter has been unlocked and detached. A hasp is shown at 28 and engages a staple 29, the hasp being secured by the usual padlock 30. The upper member 13 may be mortised into the end members 20 as shown at 31.

55 A longitudinally extending handle 33 is connected with the upwardly projecting portions of the end members, and a strap 35 is connected at its ends with the end sections 20 as shown at 36. Loops or clips for the 60 straps may be provided where needed, certain of these being shown at 37. Slots 38 are formed in one of the end members in order that a saw or saws of greater length than the box may readily be carried. Slots 65 39 permit of the insertion of the cover in a horizontal position in order that it may serve as a shelf.

55 What is claimed is:

In a device of the class described, a main 70 receptacle including front and rear walls, a bottom, an upper section covering a portion of the top and a detachable section covering the remainder of the top, guides carried by the front section near the end portions 75 of the receptacle and adapted to receive the detached cover when removed, a drawer and means for supporting the latter in the receptacle, said drawer being movable toward the opening closed by the detachable cover 80 and retained in position by the cover when the latter is in position for closing the receptacle.

In testimony whereof I affix my signature.

NICHOLAS SCHOLTES.
